(57) **CLAIM**

The ornamental design for a recoil reducer for firearms, as shown and described.

DESCRIPTION

FIG. 1 is a perspective view taken from the top and rear of the recoil reducer for firearms showing my new design;

FIG. 2 is a front elevational view of the recoil reducer for firearms of my invention;

FIG. 3 is a rear elevational view thereof;

FIG. 4 is a side elevational view thereof, the opposite side being a mirror image thereof;

FIG. 5 is a top elevational view thereof; and,

FIG. 6 is a bottom elevational view thereof.
